(57) **CLAIM**

The ornamental design for a medical device connector, as shown and described.

DESCRIPTION

FIG. 1 is a top perspective view of a medical device connector;

FIG. 2 is an enlarged view of a left perspective of the medical device connector shown in FIG. 1;

FIG. 3 is a top view thereof;

FIG. 4 is a front side view thereof;

FIG. 5 is a back view thereof; and,

FIG. 6 is a side view thereof.

The dashed-lines represent the remainder of the article and do not form part of the claimed design, are directed to environment, and represent unclaimed subject matter. The undulating thin lines located on each pin of the medical device connector represent a boundary of the claimed design and form no part of the claimed design.
